UNITED STATES PATENT OFFICE.

FRANCIS JOSEPH FREESE, OF MONTREAL, CANADA.

SOLE-CUTTING MACHINE.

SPECIFICATION forming part of Letters Patent No. 607,165, dated July 12, 1898.

Application filed August 22, 1894. Serial No. 521,045. (No model.)

To all whom it may concern:

Be it known that I, FRANCIS JOSEPH FREESE, of the city of Montreal, in the district of Montreal and Province of Quebec, Canada, have 5 invented certain new and useful Improvements in Sole-Cutting Machines; and I do hereby declare that the following is a full, clear, and exact description of the same.

This invention relates to machines for cutting blanks for shoe-soles, &c., and has for its object the general improvement of such machines with a view to producing a power-driven machine which secures, first, the easier cutting of the blank and the freeing of it from 10 the die or cutter without using any additional means for so doing; secondly, the adjustment of the die or cutter to produce various sizes and shapes of blanks; thirdly, the use of a movable stock-supporting table which presents 15 a different part of its surface to each impact of the die, thus maintaining an even surface, and allows of a ready adjustment of the stock into position to be cut by the die and of retaining it in such position, the table 20 furthermore being adjustable in working distance relatively to the die for various purposes, and, lastly, the possibility of stopping the machine at any desired point in its operation.

30 The invention consists in the several devices, arrangements, and combinations of parts hereinafter described, and particularly pointed out in the claims, and for full comprehension thereof reference must be had to the 35 annexed drawings, forming a part of this specification, in which like symbols indicate corresponding parts, and wherein—

Figure 1 is a front elevation of the complete machine; Fig. 2, a side elevation of same; 40 Fig. 3, a side elevation of same similar to Fig. 2, but partly broken away; Fig. 4, a horizontal section of machine on line $\alpha\alpha$; Fig. 1, looking in the direction indicated by arrows. Fig. 5 is a horizontal section on line yy ; Fig. 1, Figs. 6 45 and 8 being enlarged detail front views of the mechanism for operating the cutter. Fig. 7 is an enlarged detail view of the upper front portion of the machine with face-plate removed. Fig. 9 is an enlarged vertical section 50 of the upper front portion of the machine, taken on line $\alpha\alpha$; Fig. 7. Fig. 10 is a similar view to Fig. 9 of the same parts, but which

are in different positions. Fig. 11 is a horizontal section of the die or cutter on line Z Z, Fig. 7, and looking in the direction indicated, Fig. 12 being a detail view of the clutch-shipper and Fig. 13 being a detail perspective view of auxiliary widening-plate.

Heretofore in the class of work known as "sole-cutting" it has been the practice to use 60 hand-operated parts and devices with consequent loss of time and considerable expense, and to avoid such objections I provide a power-driven machine having a main driving-shaft carrying eccentrics acting directly 65 upon the carrying parts for the cutter or die, with a consequent direct and more powerful and positive operation of such die, and in order to avoid any necessity for the use of special means for freeing the blanks from the die 70 after being cut I make such die in two parts, each operated independently and alternately, so that when one part has finished cutting a portion of the blank and is withdrawing the other comes into engagement with the work 75 and in the act of cutting the remaining portion of the blank disengages it from the previously-operating part.

11 are suitable legs supporting a table 2, having a centrally-located web 3 extending 80 vertically therefrom and having recesses or portions cut away at 4, 5, and 6 to accommodate, respectively, the supporting-table, the eccentrics for operating the cutter, and the clutch-shipper, and such web also having enlargements 7 and 8, which are cored and in which are respectively located the parts carrying the supporting-table and the main operating-shaft with its clutch, a third enlargement 9 having a vertical recess, which is covered by a removable face-plate 10.

11 is the main driving-shaft, which carries a driving-pulley 12, clutch mechanism to be hereinafter described, and eccentrics 13 and 14.

15 and 16 are vertically-operating slides or parts carrying the cutters 17 and 18 and located in the vertical recess in the enlargement 9. These slides are slotted, as at 19, about midway of their length, and in the slots 100 are located springs 20, which bear downward at one end upon a fixed bar 21 (passing through the face-plate 10 and the slots into the web behind the slides) and at the other

end upward against the top end of the slots in order to normally elevate such slides into contact with the eccentrics 13 and 14, the lower ends of the slides being diminished in 5 thickness and bent at right angles to form flanges 22, to which the cutters can be secured in any desired way, but preferably by bolts passing through back plates, to which the cutting parts proper of the cutter are set 10 cured.

The cutter or die proper, as illustrated more particularly in Fig. 11, is divided into two parts preferably by a dividing cut extending longitudinally and centrally of the cutter, 15 and each part comprises an inner body or frame piece *a*, which is formed integral with a back plate *b*, and has its outer side or edge shaped to conform to that of the removable cutting blade or strip *c*, attached to it, as 20 shown in detail in Fig. 11, by screws *c'*, having shoulders *c²* *c²* formed in one therewith and between which the strip *c* is located, so that upon the screws being turned in or out 25 the cutting form or contour can be varied to a considerable extent.

In order to facilitate the shaping of the edge of the frame-piece, it is originally formed with a series of notches or recesses *d*, thus diminishing the amount of metal to be operated upon in shaping.

To enlarge or laterally expand the size of the cutter as a whole, an auxiliary or enlarging cutting plate or section comprising a frame-piece *e* and cutting-blades *f f* at each 35 end is inserted between the two parts of the cutter and secured to either of them, but preferably to the one 18 by screws *g*. The part 17 of the cutter is secured to the flange of carrier-slide 15 by bolts *h*, passing through 40 slots *j* in the flange and entering its back plate, and after being adjusted sidewise into its proper central position remains in such position, while the part 18 is similarly secured to the flange 22 of the carrier-slide 16; but 45 the slots *k* in the flange in this case are wider to allow of adjustment in any direction, as will be required in setting it in proper position relatively to the other part 17, and also when the cutter or die as a whole is being 50 widened by the insertion of the auxiliary plate *e f*. (Shown in detail in Fig. 13.)

The work support or table may be the enlargement of the web suitably faced for different kinds of work; but I prefer to use a 55 separate table of a special form and carried by such enlargement. This table is constructed so as to be rotated and have a vertical adjustment as follows:

23 is a base, preferably of metal, and having 60 upward projections 24, perforated, as at 25, and cast in one therewith. Upon the base rest two rings or annuli 26 27, each having one edge cut to form an inclined plane, the inclined plane of one corresponding with the 65 inclined plane of the other, so that when they are set one on top of the other, with their inclined faces in contact, as shown in Figs. 9

and 10, the top edge of the uppermost ring 27 will be parallel with base 23. The upper inclined edge of the lower ring 27 has a notch 70 or recess 27^a to receive a square screw-bolt 27^b, having a round screw-threaded end to receive a nut 27^c, a portion of which and a portion of the head of the bolt overlapping the lower inclined edge of the upper ring 27, 75 and when such nut is tightened will clip the upper and lower rings and retain them. Upon the uppermost of these rings is placed a circular block of wood or other like material, which is secured in place by screws passing 80 through the perforations 25 in projections 24, which projections extend upward a sufficient distance to allow of such connection.

From the under side of and having a screw-threaded connection with base 23 a vertical 85 shaft 28 projects downward through the perforation 29 in enlargement 7 to accommodate it, through the forward forked end 30 of a bracket 31, secured to the under side of table-section 2, and also through a gear-wheel 32, 90 carried by such bracket and with which gear-wheel it (the vertical shaft 28) has a feather-and-spline connection. Bracket 31 has a lateral extension 33, perforated to form a bearing for a horizontal shaft 34, carrying on its 95 forward end a worm 35 to mesh with gear-wheel 32. The other or rear end of this shaft is carried in bracket 36 and carries near its end a ratchet-wheel 37, which latter and the shaft 28 are operated by means to be presently 100 described. The table is yieldingly normally elevated into contact with the cutter by means of springs 36^x, located in sockets 37^x in the upper face of the enlargement 7 of the web, and having their upper ends bearing beneath 105 the under side of the base 23 of the table, and in order to lower the table to allow of the stock being placed between it and the cutter a treadle 38, fulcrumed at 39, is connected by means of a chain 40 and swiveling joint 41 110 to the lower end of shaft 28, such swiveling joint being necessary, so as not to interfere with the rotation of the table.

In order that the machine can be stopped at any desired point in its operation, I prefer 115 to use the form of clutch and operating mechanism therefor now to be described. The clutch proper consists of a sleeve 42, having a feather-and-spline connection with the driving-shaft 11, so as to be capable of sliding 120 thereon and rotating same when moved into clutch with the clutch-face of driving-wheel 12, which movement is effected by means of a spring 43, located in a recess 44, formed in the enlargement 8 and encircling 125 the shaft 11, the spring bearing at one end against the inner end of the sleeve 42, entering an enlargement of the outer end of the recess 44, while the other end of the spring bears against the inner end of the recess. The 130 clutch-sleeve 42 is normally held out of engagement with the driving-pulley by means of a projection 45 on its periphery, which engages the upper end of the vertical arm of a

bell-crank lever 46, fulcrumed at 47 to the web 3. This vertical arm is normally kept in a position to allow of the engagement of projection 45 therewith by means of a spring 51, bearing upward upon the underside of treadle 49, fulcrumed at 50, and the rod 48, having its lower and upper ends connected, respectively, to the treadle and horizontal arm of the bell-crank lever. By the depression of the treadle the vertical arm of bell-crank lever 46 is thrown laterally out of the way of the projection 45, thus allowing the clutch-sleeve 42 to be thrown forward by the spring 43 into clutch with the driving-pulley and the driving-shaft thereby rotated.

As a single rotation of the driving-shaft is sufficient to enable the cutter to complete its work and as it is desirable to stop the machine immediately after, I arrange for the automatic disengaging of the clutch-sleeve from the driving-pulley by forming the upper end of the vertical arm of the bell-crank lever 46 with an inclined face, with which the projection 45 (preferably also formed with a correspondingly-inclined face) on the sleeve 42 engages as the single rotation of the driving-shaft finishes, so that the sleeve is forced out of clutch with the driving-pulley and the driving-shaft consequently stopped. In order that an absolute determining of the time at which the driving-shaft will cease its rotation or a perfect adjustment of parts to that end can be secured, I prefer to make the end of the vertical arm of the bell-crank lever in a separate piece and adjustably connect same with the arm proper by slot 52 and set-screws 53.

As previously mentioned, the work-supporting table is connected with the shaft 34, carrying the ratchet-wheel 37, and in order that it may be intermittently rotated through such and the other parts described a pawl 54 is carried by the rod 48 to engage the ratchet upon each depression of the rod, with the result that the table is rotated for an extremely short distance, allowing the table to continually present a different part of its surface to each impact of the cutter, thus maintaining an even surface.

The normal position of the operating parts of my machine is as shown in Fig. 1.

In the operation of my machine the table 23 is first drawn away from the cutter or die by depressing treadle 38 to allow the stock to be set in place, as shown in Fig. 2, after which on the treadle being released the table will, through the action of springs 36, press the work up against the cutter. (See Fig. 10.) Treadle 49 is then depressed, which, through rod 48, causes vertical arm of bell-crank lever 46 to release projection 45 of clutch-sleeve 42 and allow spring 43 to force the latter into engagement with driving-pulley 12, thereby causing the rotation of main shaft 11 and with it eccentrics 13 and 14. By the downward travel of rod 48, caused by the depression of treadle 49, pawl 54, carried by such rod, en-

gages ratchet-wheel 37 and through it, horizontal shaft 34, worm 35, gear-wheel 32, and vertical shaft 28 rotates the work-table a small degree and presents a smooth surface for the dies to cut upon. As will be seen by reference to Figs. 6 and 7, eccentric 13 will commence action first and through slide 15 will cause the part 17 of the die to cut one-half of the required blank, as shown in Fig. 9, and as it completes its downward and commences its upward stroke the eccentric 14 will have caused, through slide 16, the part 18 of the die to reach and commence cutting the stock and at the same time hold the stock against displacement by part 17 as it is raised through its carrier by spring 20. The part 18 of the die, finishing its downward stroke, completes the blank and commences its upward stroke; but as it only has contact with half of the perimeter of the blank the friction will not be sufficient to cause part 18 to raise it from the table. Just before the main shaft during its rotation carries the eccentrics 13 and 14 around to the position shown in Fig. 6 to allow the springs 20 to raise the dies (through their carriers 15 and 16) to their highest point the projection 45 of clutch-sleeve 42 comes into contact with the inclined upper end of the vertical arm of bell-crank lever 46, and as it continues in its rotation for a small degree further such projection 45 is caused to travel down incline 51, force the clutch-sleeve 42 out of engagement with driving-pulley 12, and stop the machine just as the dies reach their highest point.

To insure the severance of any undesirable waste from the remaining stock after the operation of cutting a blank and to leave the stock with a comparatively even edge, I secure to the portion 18 of the cutter or die, as will be seen by reference to Figs. 7 and 11, two auxiliary blades or cutters 71 and 72, extending a sufficient distance laterally from the die (see Fig. 7) to sever the waste upon the depression of the portion 18 of the die.

What I claim is as follows:

1. In a sole-cutting machine, the combination of a frame, a work-support and a portion of said frame overhanging the work-support and having a vertical guideway therein and a divided cutter or die, the parts of which coincide to produce a complete die, with a pair of plungers located in said guideway for carrying the parts of the cutter and means for imparting alternative reciprocating motion in parallel lines of movement to the parts of said cutter or die for the purpose set forth.

2. In a sole-cutting machine, the combination of a frame, a movable or traveling work support or table and a portion of said frame overhanging the work-support and having a vertical guideway therein and a divided cutter or die, the parts of which coincide to produce a complete die with a pair of plungers having parallel movement, for actuating same, for the purposes set forth.

3. In a sole-cutting machine, the combina-

- tion of a frame, a yielding and movable or traveling work support or table, and a portion of said frame overhanging the work-support and having a vertical guideway therein and 5 a divided cutter or die, with a pair of plungers, means for actuating said table and imparting alternative reciprocating motion in parallel lines of movement to the parts of said cutter or die, for the purpose set forth.
- 10 4. In a sole-cutting machine, the combination of a frame, a yielding work-support and a portion of said frame overhanging the work-support and having a vertical guideway therein and a divided cutter or die with a pair of 15 plungers, means for imparting alternative reciprocating motion in parallel lines of movement to the parts of said cutter or die for the purpose set forth.
- 15 5. In a sole-cutting machine having a vertically-reciprocating cutter or die, a yielding work-support normally held in contact with the cutter or die and adapted with such cutter to maintain a constant pressure upon both 20 sides of the stock, for the purpose set forth, and adapted to be depressed for a limited distance, with means for limiting such depression.
- 20 6. In a sole-cutting machine, the combination of a frame, a yielding work support or 30 table adapted to yield vertically and travel in a horizontal plane and a portion of said frame overhanging the work-support and having a vertical guideway therein and a divided cutter or die with a pair of plungers, means 35 for imparting alternative reciprocating motion in parallel lines of movement to the parts of said cutter or die, for the purposes set forth.
- 25 7. In a sole-cutting machine, the combination of a frame, a cutter or die and a yielding 40 work support or table normally held by a spring in contact with the cutter or die, and a support for such table limiting the depression of same and such table adapted to be depressed for the distance determined by such 45 support, and further adapted with such cutter to maintain a constant pressure upon both sides of the stock, to travel in a horizontal plane and be adjusted in working distance relatively to said cutter or die and means for 50 actuating said die and effecting the travel of said work-support and of adjusting same, for the purposes set forth.
- 30 8. In a sole-cutting machine, the combination of a frame, a divided cutter or die, the 55 parts of which coincide to produce a complete die and a yielding work-support adjustable in working distance relatively to said cutter or die and a portion of said frame overhanging the work-support and having a vertical 60 guideway therein with means for actuating said cutter or die and of adjusting said work-support, for the purpose set forth.
- 35 9. In a sole-cutting machine, the combination of a frame, a driving-shaft carried therein, 65 a work-support and a portion of said frame overhanging the work-support and having a

vertical guideway therein, a divided cutter or die, the parts of which coincide to form a complete die, a pair of carriers or plungers located in said guideway for carrying the 70 parts of said cutter, a pair of disks mounted eccentrically upon said shaft acting to depress said carriers and springs normally elevating same for the purpose set forth.

10. In a sole-cutting machine, the combination of a frame, a driving-shaft carried therein, a work-support, and a portion of said frame overhanging the work-support and having a vertical guideway therein, a depressible divided cutter or die with its parts normally 75 elevated, and a pair of disks eccentrically carried by said shaft for acting upon the cutter-carrying parts to depress same in parallel lines of movement.

11. In a sole-cutting machine, the combination of a frame, a driving-shaft carried therein, a vertically-movable cutter or die, a yielding work-support normally held in contact with the movable cutter or die, a driving-pulley mounted loosely on said shaft and clutch 80 mechanism for connecting and disconnecting said pulley with the shaft for the purpose set forth.

12. In a sole-cutting machine, the combination of a frame, a driving-shaft carried therein, a vertically-movable cutter or die, a yielding work-support normally held in contact with the movable cutter or die, a driving-pulley mounted loosely on said shaft and clutch 85 mechanism carried in part by said pulley and 90 in part by said shaft with which the latter part has a sliding connection with means for connecting and disconnecting the parts as and for the purpose set forth.

13. In a sole-cutting machine, the combination of a frame, a driving-shaft carried therein, a vertically-movable cutter or die, a yielding work-support normally held in contact with the movable cutter or die, a driving-pulley mounted loosely on said shaft and adjustable clutch mechanism for connecting and disconnecting said pulley with the shaft as and for the purpose set forth.

14. In a cutter, a stationary interior frame or body piece and an outer encircling cutter 105 or die with continuous transformable cutting edge adjustably carried thereby and variable in form thereon.

15. A divided cutter or die having a pair of interior integral body-pieces and a pair of integral outer encircling edge pieces adjustably secured to the outer faces of such body-pieces and the ends of the separate parts of which edge pieces abut each other and coincide to produce a complete die, for the purpose set 110 forth.

16. A cutter or die formed in two cutting parts the ends of which abut each other and coincide to produce a complete die and which are independently operative with a plunger or carrier for independently carrying each part upon its end and operating same in par- 115 120 125 130

- allel lines of movement, for the purpose set forth. 5
17. The combination with the cutter or die formed of two main cutting parts adapted to be independently carried and operated and either of which is adjustable, of an auxiliary or enlarging plate or section carrying two cutting edges and adapted to be interposed between and attached to either of said main cutting parts for the purpose set forth. 10
18. The combination with the cutter formed of the two main cutting parts comprising frame-pieces and cutting blades or strips attached therein adapted to be independently carried and operated and either of which parts is adjustable, of an auxiliary or enlarging cutting part fitting longitudinally of the dies and comprising a frame-piece with cutting-blades at each end adapted to be interposed between and attached to either of said main cutting parts, for the purpose set forth. 15
19. The cutter or die formed of two main cutting parts, and an auxiliary or enlarging cutting plate or section having a body portion and cutting-blades at each end thereof and adapted to be interposed longitudinally between the main cutting parts to locate such cutting-blades in line with the blades of the main cutting parts for the purpose set forth. 20
20. The cutter or die formed of two main cutting parts comprising integral stationary frame-pieces and separate continuous flexible cutting blades or strips removably attached and adapted to conform to the outer configuration of the sides thereof, said frame-pieces having their side edges to which said blades are attached formed with a series of notches or recesses for the purpose set forth. 25
21. A cutter or die having a frame or body piece and a movable flexible cutting blade or strip attached to the edge thereof by means of screws mounted so as to rotate but held against longitudinal movement in said blade and entering said frame-piece, for the purpose set forth. 30
22. A cutter or die having a frame or body piece and a removable flexible cutting blade or strip attached to the side edge thereof, such side edge being formed with a series of notches or recesses for the purpose set forth. 35
23. In a cutting-machine, a divided cutter or die, the parts of which coincide to produce a complete die, and means for imparting alternative reciprocating motion in parallel lines of movement to said parts, for the purpose set forth. 40
24. In a sole-cutting machine, a rotatable work-supporting table having a base mounted on a suitable rotating spindle, a detachable top or block to carry the work, intermediate annular bearing sections or rings each having two separate inclined faces and means for retaining the parts in position when adjusted for the purpose set forth. 45
25. In a sole-cutting machine, a work-supporting table having a base, an adjustable top or block to carry the work and a pair of intermediate annular bearing-rings each having inclined faces movable relatively to the other with clamping devices passing through and clipping such rings for the purpose set forth. 50
26. In a sole-cutting machine, a rotatable work-supporting table having a base with upwardly-projecting lugs carrying set-screws, an adjustable top or block to carry the work, intermediate annular bearing sections or rings, each having an inclined face adapted to be moved one upon the other and clamping devices passing through said sections between their edges and adapted to clip both edges for securing such sections in position when adjusted for the purpose set forth. 55
27. The combination with the frame, the vertically-movable cutter or die, the rotatable work-supporting table and the vertical shaft carrying same, of a gear-wheel supported by the frame and having a rotary connection with said shaft, a counter-shaft suitably carried, a worm on said counter-shaft in mesh with said gear-wheel, a ratchet on said counter-shaft and an operating-pawl movable into and out of engagement with said ratchet for the purpose set forth. 60
28. In a sole-cutting machine, the combination of a driving-shaft, a divided cutter or die the parts of which coincide to produce a complete cutter or die, a work-support, an operative connection between said cutter or die and the driving-shaft, means for operating said driving-shaft and adjustable mechanism for connecting and disconnecting said driving-shaft and its means of operation, for the purpose set forth. 65

FRANCIS JOSEPH FREESE.
